[57] CLAIM

The ornamental design for a combined pacifier and a holder therefor, as shown.

DESCRIPTION

FIG. 1 is a front perspective view of a combined pacifier embodying my new design;

FIG. 2 is a rear perspective view thereof;

FIG. 3 is a front elevational view thereof;

FIG. 4 is a rear elevational view thereof;

FIG. 5 is a bottom plan view thereof;
FIG. 6 is a top plan view thereof;
FIG. 7 is a left side elevational view thereof;
FIG. 8 is a right side elevational view thereof;
FIG. 9 is a front perspective view of a second embodiment of my new pacifier;
FIG. 10 is a rear perspective view thereof;
FIG. 11 is a front elevational view thereof;
FIG. 12 is a rear elevational view thereof;
FIG. 13 is a bottom plan view thereof;
FIG. 14 is a top plan view thereof;
FIG. 15 is a left side elevational view thereof;
FIG. 16 is a right side elevational view thereof;
FIG. 17 is a front perspective view of a third embodiment of my new pacifier;
FIG. 18 is a rear perspective view thereof;
FIG. 19 is a front elevational view thereof;
FIG. 20 is a rear elevational view thereof;
FIG. 21 is a bottom plan view thereof;
FIG. 22 is a top plan view thereof;
FIG. 23 is a left side elevational view thereof;
FIG. 24 is a right side elevational view thereof;
FIG. 25 is a perspective view of a holder for my new pacifier;
FIG. 26 is a top plan view thereof;
FIG. 27 is a bottom plan view thereof;
FIG. 28 is a side elevational view thereof;
FIG. 29 is an end elevational view thereof;
FIG. 30 is a perspective view of the holder with the second embodiment of my new pacifier received therein;
FIG. 31 is a top plan view thereof;
FIG. 32 is a bottom plan view thereof;
FIG. 33 is a side elevational view thereof; and,
FIG. 34 is an end elevational view thereof.
